SEWING MACHINE

Lawrence E. Miller, Muskegon, Mich., assignor to Rockford Sewing Machine Co., Rockford, Ill., a corporation of Illinois

Filed July 8, 1957, Ser. No. 670,574
21 Claims. (Cl. 112—158)

This invention relates to sewing machines and more particularly what have come to be known as "zig-zaggers."

Zig-zag sewing machines have been available for some time equipped with a manual zig-zag control lever on the head, which, when disposed in one extreme position, causes the machine to operate as a conventional straight sewing machine, and which, when shifted more or less toward another extreme position, causes the machine to stitch zig-zag, the amplitude of the needle's zig-zag movements depending upon the position of the lever. Some sewing machines have also appeared on the market in which the mere depression of any one of a series of control buttons determines the particular zig-zag stitch obtainable out of a number of such stitches, according to the number of control buttons provided. The latter machines are much more complicated and expensive than the machines first described. It is, therefore, the principal object of my invention to provide a zig-zag sewing machine retaining all of the advantages of the first mentioned machines, while giving the advantages of the other machines with much less complications and expense.

In accordance with my invention an automatic zig-zag mechanism is installed in an existing machine without rebuilding the same, and the same operates the manual control lever and depends for its operation upon the application to a cam shaft in the mechanism of a selected cam, of which any suitable number may be provided, each giving its own individual pattern, the manual control lever, in the absence of the cam being operable just as freely as before the automatic mechanism was applied. Among the cams is preferably included one which when applied to the cam shaft gives straight sewing, the manual control lever in such case being rendered inoperable.

The zig-zag control mechanism of my invention includes the following novel features and important advantages:

(1) A two-to-one ratio between the cam shaft and the mechanism operated thereby cuts the loading in half, so that there is no danger of overloading the motor, and consequently no need of changing motors.

(2) By virtue of the two-to-one ratio between the needle and cam, two stitches can be made during each dwell of the control cam, and hence, assuming a cam is profiled with a view to providing thirty-two dwells, there are sixty-four stitches, thus making possible longer patterns and many designs that would not otherwise be possible with less stitches per cycle.

(3) A brake is provided for frictionally holding the cam in each indexed position to insure close uniformity in the repetition of a pattern, the brake element being preferably molded of nylon to reduce wear, give quiet operation, and eliminate the necessity for lubrication.

(4) The pattern cams applicable interchangeably to the cam shaft are individually marked with an illustration of the pattern obtainable with it, whereby to eliminate the need of referring to a chart or instruction book, and, what is even more important, avoid spoilage of a garment or piece of material by reason of a mistake in the selection of the cam, each cam being furthermore provided with a starting index mark, which, when set to a mark on the head, enables starting zig-zag sewing of the pattern exactly where desired, this feature being also especially handy in the stitching of buttonholes and of advantage where the operator desires to exercise her ingenuity in

2

order to obtain interesting variations in patterns by manually indexing the cam.

(5) The pattern cams are preferably molded of nylon to obtain the same advantages mentioned above in regard to the nylon brake sleeve and to make it possible to have enough elasticity in the hub portion of each cam to take care of slight variations in the sizes of the cam shaft so that the cams will hold without the help of a set screw and can, therefore, be put on and taken off so much more readily.

(6) A roller is used as the cam follower for free and easy movement on the cam, and for a similar reason a roller is provided where movement is given the zig-zag control lever by the cam follower arm, the latter having its motion transmitting end disposed as near as possible to the plane of the slide block to avoid binding, the aim being thereby to make available the same full width of pattern with this automatic mechanism as was heretofore obtainable only with manual operation.

(7) The automatic zig-zag mechanism is mounted on the cam shaft on top of the head, where it is easily accessible and can be installed most easily, and where different cams can be most easily applied for sewing different patterns. Allowance is made in the mounting of the mechanism for a certain amount of oscillatory adjustment relative to the cam shaft of the arm carrying the mechanism so that the cam follower is certain of being in the proper relationship to the high and low portions of the cam, regardless of anticipated run-out in any given machine. The present mechanism is also designed to give the zig-zag lever as wide a range of movement, necessary for full width of pattern, as in manual operation.

The invention is illustrated in the accompanying drawing, in which—

FIG. 1 is a perspective view of the head of a zig-zag sewing machine embodying my invention, both the hood and the pattern cam being removed to enable better illustration;

FIG. 2 is a vertical section through the head as it appears before the automatic mechanism is applied, namely, with only the manual zig-zag control;

FIG. 3 is a plan view of FIG. 1;

FIG. 4 is a section on the line 4—4 of FIG. 3;

FIG. 4A is a plan view of a portion of FIG. 4;

FIGS. 5 and 6 are top and bottom perspective views of one of the pattern cams;

FIG. 6A is a view like FIG. 6 of a pattern cam for straight sewing;

FIG. 7 is an exploded perspective view of the mechanism seen in FIGS. 4 and 4A;

FIGS. 8 and 9 are plan views on line 8—8 of FIG. 2 for an action study of the zig-zag sewing machine with only manual control, the control lever being shown in a maximum position, and

FIGS. 10 and 11 are views similar to FIGS. 8 and 9 but showing automatic control, these views being related to FIG. 1, FIG. 10 having its central portion taken on the line 10—10 of FIG. 4, and FIG. 11 having its central portion taken on the line 11—11 of FIG. 4, FIG. 11 showing the lever in dotted lines in maximum position and in full lines in minimum or straight sewing position, for which latter position the special cam of FIG. 6A is interchangeable with cams like that of FIGS. 5 and 6.

The same reference numerals are applied to corresponding parts through the views.

Referring first to FIGS. 2, 8 and 9, the reference numeral 12 designates the manual control lever, which, as shown in FIG. 1, is shiftable laterally in a slot 13 in the head 14 to turn a slide or swivel block 15 about its vertical pivot 16 relative to the supporting arm 17 more or less from a straight sewing or zero position, depending upon the width of zig-zag stitching desired, the lever 12

being shown in FIGS. 8 and 9 in maximum position as when shifted to the numeral 5 in FIG. 1, and being shown in minimum position in FIG. 2 for straight sewing, corresponding to the zero position of FIG. 1. The slide block 15 has a diametrically extending groove 18 provided therein in which a block pivoted on the lower end portion of a cross-pin 19 is reciprocable so that, according to the angularity for which lever 12 is set, the frame 20, which is oscillated by a cam 21 in timed relationship to the reciprocation of the needle bar 22 and connected to a crank 23 by an arm 24, will transmit a proportionate amplitude of oscillation to the needle bar carrier 25 to which the crank 23 is pivotally connected by a link 26. The cam 21 is segmental shaped and is in one or the other of its dead center or dwell positions at the opposite extremes of movement of the needle 27, the "up" position being shown in FIG. 8 and the "down" position in FIG. 9, and, inasmuch as the cam 21 is turned in timed relationship to the operation of the needle, as by a bevel gear 28 integral with the cam meshing with a bevel pinion 29 fixed on the driven shaft 30, while the latter is connected by crank 31 and pitman rod 32 with the needle bar 22, it should be clear that there is no danger of needle breakage by reason of any transverse movement of the needle while in the material. The bobbin under the bedplate is also operated in timed relationship to the rest of the machine by virtue of the driving connection afforded by crank 33 on shaft 30 and pitman rod 34 connected to said crank. The usual hand-wheel 35 mounted on the outer end of shaft 30 is driven by means of a belt 36 running on pulley 37, which in turn is driven by means of another pulley 38, as indicated in FIG. 3, the latter pulley being driven by a belt 39 running on a pulley 40 mounted on the armature shaft of an electric motor 41. The latter is arranged to be started and stopped and controlled as to speed in the usual way. In passing, attention is called to the yoke 42 fixed in the head 14, as at 43, and providing a support for the shaft 44 on which the gear 28 and cam 21 are mounted for rotation. The cover plate 45, under which the frame 20 slides as a guide, is held in place by a yoke 46 fastened by means of a screw 47 threaded in a hole in the upper end of the shaft 44, and the automatic zig-zag mechanism 48 provided in accordance with my invention is assembled on the shaft 44 as a post after the screw 47 and yoke 46 are removed.

Referring now to FIGS. 1 to 7, 10 and 11, the automatic zig-zag mechanism of my invention, indicated generally by the reference numeral 48, operates the control lever 12 differently with different cams 49 to produce different specific patterns. Each of the cams 49, in accordance with my invention, is preferably marked on top both with a serial number, as at 50, and a pattern diagram, as at 51, so that the user can select the cam by number or pattern, or both, and hence there will be no likelihood of any costly mistakes being made, inasmuch as a garment, or at least a piece of material, could easily be ruined by the stitching thereon of the wrong pattern or design. To help further toward the successful use of the present invention, an index mark 52 is provided radially on the top of the cam 49 in register with an index mark 53 on the periphery, which in turn is adapted to be placed in register with an index mark 54 provided on top of the hood 55 on the head of the sewing machine, so that the user when she sets the cam with these index marks in register knows that she will obtain the pattern 51 from the starting point thereof instead of from some intermediate point. The hood 55 is the same as the hood 55' indicated in FIG. 2 originally provided on the sewing machine head but has an opening provided therein to accommodate the cam shaft 56 and cam 49 or any alternate cam of the series. As will soon appear, whenever there is no cam in place on shaft 56 (and it will be noticed that the cams 49 have D-holes 57 provided therein permitting mounting thereof on the milled-off end 58 of the cam

shaft 56 in only one position) the machine may be operated with manual control of lever 12 the same as before the automatic zig-zag means 48 was installed. On the other hand, the series of cams 49 provided with the automatic zig-zag unit 48 may include a cam like that shown at 49' in FIG. 6A that is profiled with a concentric channel 71' for straight sewing, which when the cam 49' is applied to cam shaft 56 cooperates with the follower roller 59 to hold the lever 12 positively in the straight sewing or zero position. Inasmuch as the machine is operated to such a large extent for straight sewing it is important to avoid any likelihood of the lever 12 being tampered with by youngsters between operations of the machine, and this straight sewing cam 49' offers some insurance against such tampering. The cam 49', of course, requires no index markings 52-53 nor any pattern marking 51, unless it be a straight line to represent straight sewing. This cam 49' may, of course, be numbered on top, as indicated at 50, with a zero (indicating no pattern) or with the numeral 1 or 10 or whatever else is considered appropriate in relation to the series of cams provided. The cams 49-49' are preferably molded of nylon with a view to durability without need of lubrication and to insure quiet operation and also make for economy of production. This material also has enough elasticity so that the hubs 60 on the cams may be purposely made a trifle undersize in relation to the milled end 58 of the cam shaft 56 to take hold securely enough so that there is no need for any set screws and the elasticity in the connection will more than compensate for such slight variation in size as there is apt to occur in quantity production of the parts 56. Each hub 60 is split diametrically as shown at *a*, and has three small longitudinal ribs *b* in the bore 57, 120° apart. The ribs *b* assure a good snug fit even if the shaft 56 is undersize. If the shaft 56 is of regulation size or oversize, the slots *a* allow enough give for easy application of the cam. The cams 49-49' being on the outside of the head 14 and hood 55 can be put on and taken off easily and yet are not so easily removable that a youngster in tampering with the machine is apt to take one off. In passing, I would mention that the ratchet 61 and associated pawl 62, which form an important part of the automatic zig-zag means 48, are responsible for permitting the manual turning of the cam 49 to the starting position, as above described, and further advantage may be taken of this feature by providing quarter, half, and three-quarter marks on top of the cams 49 or hood 55, or 90°, 180°, and 270°, as indicated in dotted lines at 63 in FIG. 3, so that a user, once she has gained sufficient experience with the automatic zig-zag machine, can obtain interesting changes in patterns by manually indexing the cam 49 back to the starting position after each 90° or 180° of travel, if experimenting shows that pleasing variations in patterns are obtainable that way.

The cam follower roller 59 is mounted on one end of a bell-crank lever 64 that is pivoted intermediate its end, as at 65, on a plate 66 fixed on top of a yoke 67 suitably held against turning with respect to the head 14 as by a press fit between parallel flat faces 68 provided on the inner side of the front and back walls of the head 14, where the yoke 46 previously mentioned was previously mounted. The bell-crank lever 64 has a slot 69 provided in its free end in which is slidably engaged a roller on pin 70 fixed with lever 12 to the top of slide block 15 in radially offset relationship to the pivotal axis 61 thereof, whereby to turn the slide block 15 through a certain angularity when the follower roller 59 moves one way or the other as it follows the profiled surface 71 of the cam 49. A torsion spring 72 is mounted on another pin 70' fixed like pin 70 on slide block 15 in radially offset relation to pivotal axis 16 and serves by slidable engagement at its one end with the inside of head 14 and engagement with pin 70 at its other end to urge the levers 12 and 64 normally toward the zero or straight sewing position, thereby keeping the follower roller 59 always resiliently

engaged with the cam surface 71. As will soon appear, the cam shaft 56 is turned intermittently in a counter-clockwise direction, as viewed in FIG. 3, and, hence, the lever 12 and slide block 15 are turned first in one direction and then another through different angles according to the profile of the cam to obtain zig-zag stitching of whatever pattern 51 the cam 49 in use at a given time is designed for. Two screws 73 are entered through ears 74 provided on a split brake sleeve 75 and are entered through registering holes 74' in plate 66 and threaded in registering holes 74" in yoke 67 to fasten the three parts together, holding the brake sleeve 75 against turning, so that it can serve as a friction grip for the cam shaft 56 to hold it in each indexed position. The holes 74' are large enough in relation to holes 74" to permit a predetermined amount of oscillatory adjustment of plate 66 about cam shaft 56 as an axis to secure the right relationship of the cam follower 59 to the high and low portions of the cam surface 71, regardless of any usual runout in the sewing machine. A screw 76 is entered freely through a hole in one of two ears 77 provided on the split side of the sleeve 75 and is threaded in a registering hole in the other of said ears and is arranged to be adjusted to provide the right amount of friction to hold the shaft 56 in each indexed position without causing too much drag on the operation. The screw 76 can be adjusted also to compensate for wear between the parts 56 and 75, although wear is reduced to a minimum by molding the brake sleeve 75 of nylon, this material having the further advantage of giving quiet operation even though there is and should be no lubricant present. Sleeve 75, besides serving as a brake for cam shaft 56, serves as an upper bearing for it, said shaft using shaft 44 as a lower bearing, as seen in FIG. 4.

The pawl 62 which engages the ratchet 61 to index the cam 56 is pivoted at 78 on an arm 79 oscillatable at one end 80 about the cam shaft 56 as a center. A single coil wire torsion spring 81, which is looped around the pivot 78 and has one end abutting the arm 79 and the other end abutting the pawl 62, serves to hold the pawl in spring-pressed engagement with ratchet 61. A radial slot 82 is provided in the outer end of the arm 79 for slidable pivotal connection of the arm 79 with the enlarged upper end portion 83 of the cross-pin 19 on frame 20. Hence, arm 79 is oscillated per oscillation of frame 20 by cam 21, regardless of whether the frame 20 is given much or any longitudinal movement, according to the position of the control lever 12 and slide block 15. The oscillation of arm 79 is through the same angularity with respect to the cam shaft 56 for each rotation of the cam 21, thereby indexing the cam through the same angularity by means of the pawl 62 and ratchet 61. The cam shaft 56 can at any time be turned manually in a counterclockwise direction, the ratchet 61 then overrunning the pawl 62. That was mentioned before in connection with the discussion of the cams 49. Now, it is important to note the two-to-one ratio between gears 28 and 29. The needle 27 and cam shaft 56 are, therefore, in that same two-to-one relationship, so that the needle can make two stitches for each cam dwell, and, inasmuch as the ratchet 61 has thirty-two teeth providing thirty-two dwells per cam 49, it follows that there will be sixty-four stitches per rotation of the cam 49. That makes possible longer patterns and hence many more designs that would not be possible with less stitches per cycle. It is also ideal for blind stitching where the needle must move from a minimum to a maximum position per dwell of the cam to make a stitch on each side of a hem. This ability to go from minimum to maximum in one dwell also enables stitching many patterns with intricate designs where other constructions not designed to permit such abrupt drop-off are accordingly limited as to range of patterns. In passing, it will be noticed that the arm 79 is recessed, as shown at 84, to accommodate the pawl 62, ratchet 61, and spring 81 for maximum compactness, and also enable locating the arm

79 much closer to the plane of the frame 20 to avoid binding. This same principle is applied in the case of the cam follower arm 64 which for this reason has the downwardly extending end portion 85 with the inwardly bent extremity 86 in which the slot 69 for connection with the pin 70 is provided as close to the plane of the slide block 15 as possible to avoid binding. The arm 79, as indicated by the cross-hatching of FIG. 4, is molded of nylon the same as the cams 49 and brake sleeve 75, for similar reasons. The give, which the nylon construction of arm 79 affords, is of great advantage in preventing expensive damage to the sewing machine in the event the free to and fro movement of lever 12 is blocked, as by entry of something in slot 13 in front of or behind the lever, or by setting a stop or stops, such as are provided as guides for manual oscillation of the lever. When the lever 12 is blocked and the mechanism is jammed, the slotted end 82 of arm 79 flexes harmlessly with each oscillation of frame 20. Normal operation is resumed again when the block is removed and lever 12 is free to move again.

It is believed the foregoing description conveys a good understanding of the objects and advantages of my invention. The appended claims have been drawn to cover all legitimate modifications and adaptations.

I claim:

1. In a zig-zag sewing machine, an endwise reciprocating and laterally shiftable needle-bar, an oscillatory member in which said needle bar is mounted for endwise reciprocation and lateral shifting, a rotary driven shaft operatively connected with said needle bar to reciprocate the same, a rotary cam, a frame oscillated by said cam and operatively connected to oscillate said oscillatory member laterally, means for turning said cam in synchronism with said shaft, a manually oscillatable pattern control lever, a slide block turnable with said lever having a transversely extending slot provided therein, a cross-pin on said frame slidable at its one end in said slot to transmit some or no endwise movement to said frame in the oscillation thereof relative to said slide block depending on the position of said block, an intermittently rotatable pattern cam, means operatively connected with the other end of said cross-pin for indexing said pattern cam in the oscillation of said frame, and a follower engaging said pattern cam operatively connected with said slide block to turn the same in either direction in accordance with the profile of said pattern cam.

2. A sewing machine as set forth in claim 1, wherein the means for turning the first mentioned cam in synchronism with the shaft turns said first mentioned cam at half the speed of the shaft.

3. A sewing machine as set forth in claim 1, including brake means for holding said pattern cam in indexed positions.

4. In a zig-zag sewing machine, an endwise reciprocating and laterally shiftable needle-bar, an oscillatory member in which said needle bar is mounted for endwise reciprocation and lateral shifting, a rotary driven shaft operatively connected with said needle bar to reciprocate the same, a rotary cam, a frame oscillated by said cam and operatively connected to oscillate said oscillatory member laterally, means for turning said cam in synchronism with said shaft, a manually oscillatable pattern control lever, a slide block turnable with said lever having a transversely extending slot provided therein, a cross-pin on said frame slidable at its one end in said slot to transmit some or no endwise movement to said frame in the oscillation thereof relative to said slide block depending on the position of said block, an intermittently rotatable pattern cam, means operatively connected with the other end of said cross-pin for indexing said pattern cam in the oscillation of said frame, and a follower engaging said pattern cam operatively connected with said slide block to turn the same more or less in either direction in accordance with the profile of said pattern cam, said pattern cam and follower having means whereby

they are detachably engageable, whereby to permit manual control of the pattern by operation of the control lever when the pattern is not automatically controlled by said pattern cam.

5. A sewing machine as set forth in claim 4, wherein the pattern cam is profiled for straight sewing holding the follower and control lever in straight sewing position and said pattern cam is one of a plurality of interchangeable pattern cams, each differently profiled for a different pattern.

6. A sewing machine as set forth in claim 4, wherein the pattern cam has an index mark thereon indicating the starting point of the pattern for which the pattern cam is profiled, the machine having an index mark thereon arranged to have the index mark on the pattern cam registered with it.

7. A sewing machine as set forth in claim 4, wherein the pattern cam has an index mark thereon indicating the starting point of the pattern for which the pattern cam is profiled, the machine having an index mark thereon arranged to have the index mark on the pattern cam registered with it, the pattern cam being rotatably adjustable manually relative to its indexing means to permit setting the pattern cam to zero or any other position.

8. In a zig-zag sewing machine having a needle bar carrier that is laterally shiftable and has a needle bar reciprocable therein, said machine comprising a main driven shaft operatively connected to reciprocate the needle bar, and a cam shaft fixed in right angle relation to said driven shaft rotatably mounting a cam operatively connected to be driven in synchronism with said driven shaft, a frame oscillated by said cam and operatively connected with said needle bar carrier to shift it back and forth laterally with variable amplitude, and a swivel control element operatively connected with said frame so that the position of the element determines the amplitude between zero and maximum, the improvement which consists in the provision of a secondary cam shaft that is hollow at one end and telescopes on the aforesaid cam shaft and carries a ratchet wheel, a pattern cam detachably mountable on said secondary cam shaft to turn intermittently therewith, a cam follower engaging said pattern cam, means operated by said follower and operatively connected with said swivel control element to shift the latter in response to lateral movement of the follower, and means operatively connected to oscillate with said frame and carrying a pawl engaging the ratchet wheel so as to index said pattern cam.

9. A sewing machine as set forth in claim 8, including a brake for holding said secondary cam shaft against turning between indexes thereof.

10. In a zig-zag sewing machine having a needle bar carrier that is laterally shiftable and has a needle bar reciprocable therein, said machine comprising a main driven shaft operatively connected to reciprocate the needle bar, and a cam shaft fixed in right angle relation to said driven shaft rotatably mounting a cam operatively connected to be driven in synchronism with said driven shaft, a frame oscillated by said cam and operatively connected with said needle bar carrier to shift it back and forth laterally with variable amplitude, and a swivel control element operatively connected with said frame so that the position of the element determines the amplitude between zero and maximum, the improvement which consists in the provision of a secondary cam shaft that is hollow at one end and telescopes on the aforesaid cam shaft and carries a ratchet wheel, a pawl engaging said ratchet wheel and pivotally mounted on an arm oscillatable relative to said secondary cam shaft, said arm being operatively connected with said frame for oscillation thereby, a supporting bracket fixed in the machine having a hole provided therein, a plate carried on said bracket having a registering hole provided therein, said secondary cam shaft projecting through said holes, means securing said plate to said bracket permitting some rotary adjustment of the plate relative to the bracket

about said secondary cam shaft as a center, an arm pivotally mounted intermediate its ends on said plate carrying a cam follower on one end and having an operative connection at its other end with the control element to shift the latter back and forth with the oscillation of said arm, and a pattern cam mounted on the secondary cam shaft and engaged by said follower.

11. A sewing machine as set forth in claim 10, including a brake collar carried on said bracket having said secondary cam shaft extending therethrough and held thereby against turning between indexes thereof.

12. A sewing machine as set forth in claim 10, including a brake collar carried on said bracket having said secondary cam shaft extending therethrough and held thereby against turning between indexes thereof, said collar having ears thereon with screw holes provided therefor registering with screw holes provided in the bracket, the means securing said plate to said bracket comprising screws entered in said screw holes through registering slightly larger holes in the plate, whereby said plate is rotatably adjustable and adapted to be clamped in adjusted position between the bracket and collar while also securing said collar to said bracket.

13. In a zig-zag sewing machine having a needle bar carrier that is laterally shiftable and has a needle bar reciprocable therein, said machine comprising a main driven shaft operatively connected to reciprocate the needle bar, and a cam shaft fixed in right angle relation to said driven shaft rotatably mounting a cam operatively connected to be driven in synchronism with said driven shaft, a frame oscillated by said cam and operatively connected with said needle bar carrier to shift it back and forth laterally with variable amplitude, and a swivel control element operatively connected with said frame so that the position of the element determines the amplitude between zero and maximum, the improvement which consists in the provision of a secondary cam shaft that is hollow at one end and telescopes on the aforesaid cam shaft and carries a ratchet wheel, a plurality of pattern cams interchangeably detachably mountable on said secondary cam shaft to turn intermittently therewith, each pattern cam having a different profile for a different pattern to be sewed with zig-zag stitching, a cam follower arranged to engage a pattern cam when the latter is mounted on said secondary cam shaft, means operated by said follower and operatively connected with said control element to shift the latter in response to lateral movement of the follower, and means operatively connected to oscillate with said frame and carrying a pawl engaging the ratchet wheel so as to index said pattern cam.

14. A sewing machine as set forth in claim 13, wherein each pattern cam has an index mark thereon indicating the starting point of the pattern for which the cam is profiled, the machine having an index mark thereon arranged to have the index mark on the cam registered with it.

15. A sewing machine as set forth in claim 13, wherein each pattern cam has an index mark thereon indicating the starting point of the pattern for which the cam is profiled, the machine having an index mark thereon arranged to have the index mark on the cam registered with it, the cooperating pawl and ratchet permitting rotary setting of the cam to zero or any other position when fixed on the secondary cam shaft.

16. A sewing machine as set forth in claim 13, wherein one of the pattern cams is for straight sewing.

17. In a zig-zag sewing machine comprising a head with an arm extending therefrom on which a needle carrier bar is reciprocable and laterally movable, a manually operable pattern control lever extending from the front of said arm and shiftable laterally from a straight sewing position to determine the amplitude of zig-zag movement of the needle bar, mechanism on said arm operatively connected with said lever and driven with the needle bar to shift said lever automatically through a predetermined

cycle of movements for the zig-zag sewing of a pattern, and a plurality of pattern cams each having means thereon for detachable operating connection with means included in the aforesaid mechanism on said arm, whereby said cams are separately and directly and without the necessity for the employment of any other means applicable interchangeably to said mechanism to give different cycles of lever movements for different patterns, said mechanism including means driven in timed relation to the needle to index the cam, one part of said mechanism through which movement is transmitted in the automatic operation of said pattern control lever being resilient and yieldable, whereby to prevent damage to said mechanism in the event movement of said lever is blocked.

18. A sewing machine as set forth in claim 1 wherein at least one part of the combination described through which movement is transmitted in the automatic operation of said manually oscillatable pattern control lever is resilient and yieldable whereby to prevent damage to the sewing machine in the event movement of said lever is blocked.

19. In a zig-zag sewing machine, an endwise reciprocating and laterally shiftable needle-bar, an oscillatory member in which said needle bar is mounted for endwise reciprocation and lateral shifting, a rotary driven shaft operatively connected with said needle bar to reciprocate the same, a rotary cam, a frame oscillated by said cam and operatively connected to oscillate said oscillatory member laterally, means for turning said cam in synchronism with said shaft, a swivel block having a transversely extending slot provided therein, a cross-pin on said frame slidable at its one end in said slot to transmit some or no endwise movement to said frame in the oscillation thereof relative to said swivel block de- 35

5 pending on the position of said swivel block, an intermittently rotatable pattern cam, means operatively connected with the other end of said cross-pin for indexing said pattern cam in the oscillation of said frame, and a follower engaging said pattern cam operatively connected with said swivel block to turn the same in either direction in accordance with the profile of said pattern cam.

10 20. A sewing machine as set forth in claim 19, wherein the means for turning the first mentioned cam in synchronism with the shaft turns said first mentioned cam at half the speed of the shaft.

21. A sewing machine as set forth in claim 19, including brake means for holding said pattern cam in indexed positions.
